ASH TRAY

William T. Glass, 117 N. 5th St.,
Columbus, Miss. 39701

Filed Aug. 12, 1968, Ser. No. 13,108

Term of patent 14 years

Int. Cl. D27—03

U.S. Cl. D85—2

Fig. 4

Fig. 5

Fig. 6

FIGURE 1 is a top perspective view of an ash tray, showing one form of my new design;

FIGURE 2 is a top plan view of the form shown in FIGURE 1;

FIGURE 3 is an end elevational view of the form shown in FIGURE 1;

FIGURE 4 is a side elevational view of the form shown in FIGURE 1;

FIGURE 5 is a bottom plan view of the form shown in FIGURE 1;

FIGURE 6 is a top perspective view of an ash tray, showing a second form of my new design;

FIGURE 7 is a longitudinal vertical sectional view of the ash tray shown in FIGURE 6; and

FIGURE 8 is a top perspective view of an ash tray, showing a third form of my new design.

I claim:

The ornamental design for an ash tray, as shown and described.
